BRACKET

Russell Katz, Hamilton, Ohio, assignor to Paul Benninghofen and Eleanor C. Diesbach, trustees, Hamilton, Ohio

Application October 11, 1947, Serial No. 141,869

Term of patent 7 years

(Cl. D33—3)

To all whom it may concern:

Be it known that I, Russell Katz, a citizen of the United States, residing at Hamilton, in the county of Butler and State of Ohio, have invented a new, original, and ornamental Design for a Bracket, of which the following is a specification, reference being had to the accompanying drawing, forming a part thereof.

Figure 1 is a perspective view of the bracket, this view showing the bracket in relation to a music stand indicated in dot and dash lines for purposes of illustration.

Figure 2 is an enlarged perspective view of the bracket.

Figure 3 is a side view thereof.

Figure 4 is a rear view thereof.

I claim:

The ornamental design for a bracket, substantially as shown and described.

RUSSELL KATZ.
